CLAIM

I claim the ornamental design for a lighting fixture, as shown and described.

DESCRIPTION

FIG. 1 is a perspective view of a lighting fixture showing a first embodiment of the new design. This fixture has 180° overall rotational symmetry, and mirror image symmetry along a first vertical imaginary plane and also mirror image symmetry along a second vertical imaginary plane, with the first and second vertical imaginary planes being orthogonal to each other. The shades have a circular horizontal cross-section; and,

FIG. 2 is a perspective view of a lighting fixture showing a second embodiment of the new design. This fixture has 180° overall rotational symmetry, and mirror image symmetry along a first vertical imaginary plane and also mirror image symmetry along a second vertical imaginary plane, with the first and second vertical imaginary planes being orthogonal to each other. The shades have a circular horizontal cross-section.

The broken lines shown on the drawings depict portions of the lighting fixture that form no part of the claimed design.
